ABRAHAM GOODMAN, OF NEW YORK, AND JACOB GOODMAN, OF BROOKLYN, NEW YORK

HAIR WAVER

Application filed April 19, 1928. Serial No. 271,123.

This invention relates to an improved device for imparting to the hair a wave of natural appearance.

Among the salient objects which the present invention has in view are: To provide a hair waver which may be easily and conveniently applied to the hair in service and also conveniently removed from the hair after the desired wave has been formed; to provide a hair waver of simple, inexpensive and efficient construction; to construct the hair waver of light and inexpensive material, preferably of metal; to provide a hair waver which will function to impart the desired wave to the hair without necessitating the application of water or heat to the hair during the formation of the wave, and generally to improve the construction.

Other objects and advantages of the invention will appear as the description proceeds.

In the drawings:

Figure 1 is a side elevational view of a hair waver constructed in accordance with this invention showing the same closed as in service.

Figure 2 is a view of the hair waver looking upward as in Figure 1.

Figure 3 is a transverse sectional view through the hair waver taken as on the line 3-3 of Figure 1, the view being somewhat enlarged.

Figure 4 is a view showing a fragment of the construction on an enlarged scale, the view being partly in side elevation and partly in section.

Figure 5 is a side elevational view of a modified form of hair waver showing the same closed as in service; and

Figure 6 is a view of the modified hair waver looking at the bottom of Figure 5.

Referring now more particularly to the drawings which illustrate the preferred forms of the invention, and to the details of which the invention is not to be confined, the embodiment shown in Figures 1 to 4 includes an arched rib element 10 which is preferably constructed of a light metal such as aluminum and has an inverted channel shaped cross-section as shown in Figure 3.

50 A slotted element 11 is pivoted to one end

of the arched element 10, the arched element is adapted to move on the pivot through the slot of the element 11 into the closed position shown in Figure 1. The element 11 is preferably formed of a thin wire of a light material which comprises two branches 12 and 13 arranged in spaced relation and in parallel relation to each other and to the element 10, the portions 12 and 13 being united integrally by end loops 14 and 15.

The end loop 15 is pivotally connected to the end of the arched element 10 and to this end the arched element may be formed with slots 16 through which the loop 15 extends in which said loop is seated and is maintained therein for pivotal movement by a rearward extending tongue 17 formed integrally with the arched portion 10. The tongue is maintained in this rearward position shown in Figure 4 as by means of lugs 18 which are formed as a part of the arched portion 10 and are bent over on the tongue 17.

The elements 10 and 11 as above stated are adapted for relative pivotal movement and the element 10 may be moved freely with respect to the element 11 and through the slot therein or the space between the portions 12 and 13 until its free end strikes the loop 14 which restrains it from further movement. The free end of the arched element is preferably provided with a small detent 19, into which the loop 14 may be snapped for resiliently locking the hair waver into the closed or operative position shown in Figure 1.

In the formation of the wave in the hair, the elements 10 and 11 are opened up and the hair is arranged over the top of the arched portion 10. The element 11 is then swung into closing position shown in Figure 1 and the arched portion 10, with the hair arranged on it, is passed through the slot of the element 11 as it moves downward into operative relation and is locked in closed position by the loop 14 snapping into the detent 19. The hair waver is maintained in such position until the hair has been acted upon for a sufficient time to give the hair the desired wave after which the hair waver is removed.

The hair wavers are applied without wetting or heating the hair and may be conveniently worn at any time in private. The light weight of the hair waver is a very desirable feature as by virtue thereof the waver may be worn for a considerable length of time without discomfort, thus making the wave more enduring and lasting. The construction is also very simple and hair wavers thus constructed may be placed on the market at a low price.

The embodiment shown in Figures 5 and 6 is similar to that previously described, with the exception of the hinge or pivot construction. In the construction of Figures 5 and 6, the loop 15 passes through openings 20 formed through the arched rib portion 10 at the end thereof, the material of the end being flattened to permit the alignment of the openings. This construction is somewhat cheaper than that of the first modification, although the hinge so obtained is not quite as nice in appearance.

Various slight alterations and modifications may be resorted to in the practice of the invention and no limitations are to be imposed upon the invention other than necessitated by the state of the prior art and the scope of the appended claims.

30 Claims:

1. A hair waver comprising an arched rib element having an inverted channel shaped cross section, a slotted element formed of spaced wires arranged in parallel relation to each other and to said arched element and integrally connected by end loops, means for pivotally connecting one end loop to one end of the arched element, and means for detachably locking the other loop to the other end of the arched element when the arched element passes through the space between the wires and its free end abuts against said second loop, said locking means comprising a detent in the arched element adapted to snap into locking engagement with the second loop.

2. A hair waver comprising a rib element, a slotted element formed of spaced wire portions arranged in parallel relation to each other and to said rib element and connected by end wire loops, means for pivotally connecting an end loop to said rib element near an end thereof, said means comprising an end tongue integrally formed with said rib element and bent back on said rib element to house the end loop between itself and the rib element and means for retaining the tongue in its bent back position.

3. A hair waver comprising a molded rigid rib element having an inverted U-shaped cross section and embodying a perforation at one end for forming a hinge, and an indent at the opposite end for forming a latch member, an elongated resilient wire loop, one end of said loop being held in the perforation

in said rib member, the other adapted to engage the recess for the latch at the other end of said rib member, the elongated sides of said loop being formally outwardly bowed to hold the end of said loop in engagement with said latch member to be released therefrom by the compression of the sides of said loop.
